A. M. FLORA.
MILLINER'S HAT BAG.
APPLICATION FILED APR. 27, 1915.

1,189,082.

Patented June 27, 1916.

UNITED STATES PATENT OFFICE.

ANNA M. FLORA, OF RICHMOND, KENTUCKY.

MILLINER'S HAT-BAG.

1,189,082.

Specification of Letters Patent. Patented June 27, 1916.

Application filed April 27, 1915. Serial No. 24,307.

To all whom it may concern:

Be it known that I, ANNA M. FLORA, a citizen of the United States, residing at Richmond, in the county of Madison and 5 State of Kentucky, have invented certain new and useful Improvements in Milliners' Hat-Bags, of which the following is a specification.

My invention relates to paper receptacles 10 and more particularly to a milliner's hat bag.

The primary object of my invention resides in the provision of a bag for containing a lady's hat when it is desired to carry 15 the hat from one place to another or when the hat is not used, in order to fully protect the feathers or trimmings from dust or from being crushed or otherwise injured.

Another object of my invention resides in 20 the provision of an improved bottom for the bag of sufficient strength to maintain the hat and insure rigidity enough to the sides of the bag to prevent the sides from collapsing or bearing against the trimmings 25 of the hat that extend above the crown or from the sides of the hat, thus affording better protection than that of the ordinary paper bag now in use.

A further object of my invention resides 30 in the improved means for connecting the blank or body of the bag to the bottom for reinforcing the bottom, incidentally producing the resulting rotundity of the body.

A still further object of my invention resides 35 in the novel manner of folding the bag so that it may be conveniently folded to occupy a minimum amount of space in order that a plurality of the bags may be placed in a suitable container for shipping purposes.

A still further object of my invention resides 40 in the provision of a device of the character described that is simple in construction, efficient in operation and one that can be manufactured and placed upon the market at a minimum cost.

Other objects as well as the nature, characteristic features and scope of my invention will be more readily understood from 45 the following description taken in connection with the accompanying drawings and pointed out in the claim forming a part of this specification.

In the drawings: Figure 1 is a top plan 50 view of the blank for one of my improved bags ready for folding; Fig. 2 is a perspec-

tive view of my invention in an open position, a portion thereof being broken away to illustrate the manner of associating the bottom with the blank; and Fig. 3 is a longitudinal view illustrating the bag when folded, especially disclosing the improved means for folding the blank in order to engage the bottom for reinforcing the latter as well as producing the resulting rotundity to the bag when open.

Referring more particularly to the drawings in which similar reference numerals designate like or corresponding parts throughout the different views, I provide 70 preferably a rectangular blank formed of paper, the blank being provided with longitudinally arranged creases 1, on which the blank is foldable to provide sides 2 in a manner and for a purpose to be hereinafter 75 described. The blank is further provided with diagonally extending creases 3 on oppositely disposed sides 2, the creases 3 being arranged in intersecting planes when the edges of the blank are secured together 80 during the assembling of the bag. The blank is also provided with diagonal creases 4 which extend inwardly toward the center of the blank from the side edges thereof and at a substantially acute angle toward the 85 bottom edge as illustrated to advantage in Fig. 1 in the accompanying drawings, to serve a purpose to be hereinafter referred to.

In first assembling the blank to provide 90 the bag, the respective ends of the blank, adjacent the outer creases 1 are connected in any suitable manner, preferably by glue or like substance in such a manner that these end creases 1 will register with each other throughout their length, thus providing a 95 cylindrical body for the bag. The blank is now provided with slits 5 on two of the creases 1 as illustrated to advantage in Fig. 1, which slits extend inwardly a slight distance and when the body is arranged in a 100 circular form, are positioned at diametrically opposite points. A cardboard disk 7 is now arranged within the body and associated with the lower end thereof to provide a bottom for the bag. It is desired that the 105 cardboard be of sufficient strength to hold a lady's hat without being of more weight than necessary to insure rigidity enough to prevent the sides of the bag from collapsing or pressing against any of the trimmings 110 that may project from the sides or extend above the crown of a hat, thus affording bet-

ter protection than that of the ordinary envelop or box now in use, which does not have a flat bottom as well as eliminating the high cost of the various types of "knock-down" cardboard boxes. This bag is especially designed for the use of the retail millinery trade, that each purchaser may be provided with a reliable protecting bag in which to carry their hats away from the store.

In securing the blank or body to the bottom, the blank or sides 2 is folded on the creases 6, which creases provide a substantially octagonal lower end for the body 15 when the lower portion of the blank is secured to the bottom, in order to facilitate the bag assuming a cylindrical contour when open, and incidentally offsetting the tendency of the creases 1, which constitute the 20 angles of the body when folded, to produce a rectangular body. Through the instrumentality of glue or similar adhesive substance, the lower portion of the blank, after being folded on the creases 6 is secured to 25 the bottom 7 in such a manner that the lower longitudinal edges thereof will be arranged in closely spaced relation with each other. In finally securing the blank to the disk, the 30 portions adjacent the slits 5 are folded upon the creases 7 and 8 to provide triangular flaps 9 and 10, which are in turn folded upon the adjacent creases 6 and secured together upon the lower portion of the blank which supports the disk 7, the flaps incidentally 35 reinforcing the bottom.

In order that the bag thus formed may be folded, the sides are folded on the diagonal creases 3 so that the other sides of the blank will lie in one plane and at 40 angles to each other. When in this position the creases 4, which before the blank is folded are arranged at angles to each other, are now, because of the forming of the cylindrical body and the folding of the latter on 45 the longitudinal creases 1 and diagonal creases 3, arranged in alignment with each other, thus allowing the body in its folded and flattened form as just described, to be folded on the creases 4 and positioned in the 50 same plane as the bottom thereof for producing a milliner's hat bag that can be folded to occupy a minimum amount of space as well as one that is adapted to be extended or opened, maintaining a sufficient 55 rigidity to permit of the insertion of a hat. It is, of course, understood that the depth of the bag is immaterial since it may be of any size desired to suit the requirements of the trade.

60 Although I have shown and described the preferred embodiment of my invention, I desire to be understood that I am not to be limited to the exact details shown, however,

great stress is laid upon the novel means of folding the lower end of the blank for connecting the latter to the bottom for accomplishing the purposes set forth as well as the novel means for folding the body after it has been assembled, in order that the body may be placed in a flattened condition

70

From the above description taken in connection with the accompanying drawings, it can easily be seen that I have provided a device that is simple in construction, containing but a few simple parts that can be 75 cheaply manufactured and assembled and when assembled can be placed upon the market and sold at a minimum cost.

It will be understood that the above description and accompanying drawings comprehend only the general embodiment of my invention and that various minor changes in detail of construction, proportion and arrangement of the parts may be made within the scope of the appended claim and without sacrificing any of the advantages of my invention.

Having thus fully described my invention, what I claim as new and desire to secure by Letters Patent, is:—

90

A milliner's hat bag including a cylindrical body formed from a rectangular blank of paper having slits extending inwardly along the lower edge at uniformly spaced intervals from the side, a card-board disk, the lower portions of the body between the slits being folded and secured upon the lower surface of the disk so that the edges of the lower folded portions are arranged in close relation with each other to 100 provide an efficient connection between the body and the disk, the lower portion of the body being provided with transverse and with diagonal creases, triangular flaps formed on the lower portions of the body 105 when the portions are folded on the transverse and diagonal creases adjacent the slits for consequently reinforcing the bottom and for facilitating the cylindrical formation of the body when extended, the flaps being 110 foldable to allow one flap to engage the other and both to engage the lower folded portion of the body opposite to the lower portion from which each flap extends, and the main portion of the body provided with 115 diagonal and longitudinal creases to permit of the folding of the body into a flattened form and also provided with transverse creases to permit of the folding of a body upon itself.

120

In testimony whereof I affix my signature in presence of two witnesses.

ANNA M. FLORA.
